[57] ABSTRACT

A replaceable wringer mop head with a substantially square cross section is formed from a single piece of cellular sponge, preferably with a reinforcing mesh closely adjacent the exterior. A pair of mounting spools are located at opposed ends of the replaceable mop head, and tied securely to each end of the cellular sponge by means of a clamping ring. Both of the spools are provided with means for longitudinally engaging a corresponding fin on a wringer type mop holder which, in one position, is fixed. In the other two alternative positions, approximately 90° of freedom is afforded the mop head with regard to the shaft of the wringer mop. Upon reciprocating the mop, at each stroke reversal, alternate adjacent mop head faces engage the surface being mopped. The wringer mop is of the character in which the far end can be rotated by rotating one of the spools, and the opposite spool secured to the end that the mop head may be wrung dry of water by such rotation.

MOLDED MOP HEAD

CROSS REFERENCE TO RELATED APPLICATIONS

The improved molded mop head of the present invention is useful with a wringer mop of the character disclosed and described in Samuel J. Popeil U.S. Pat. application Ser. No. 119,160 filed Feb. 26, 1971, now U.S. Pat. No. 3,699,603 issued Oct. 24, 1972.

BACKGROUND OF THE INVENTION

The subject matter of the present invention relates to the type of wringer mop of the character disclosed in Nicholson U.S. Pat. No. 2,118,618 and Mantelet U.S. Pat. No. 3,616,483 in which the self-wringing action of the mop head is made possible by a host structure or environment.

The mop head such as shown in Mantelet U.S. Pat. No. 3,616,483 has a cloth surface which is quite thick and may impede the transition of moisture in and out of the sponge-type material. Other mop heads of the sponge type such as Brown U.S. Pat. No. 2,955,309 when used in washing walls, can be severely abraded by flecks of dirt and other impurities which become embedded in the paint on the wall. By using the reinforcing mesh such as described in Buchkremer U.S. Pat. No. 2,913,772 a much more abrasive resistant surface results.

The mop head assembly of co-pending U.S. Pat. application Ser. No. 119,160 is rectangular in cross section, and therefore the two narrow faces, because of their relative instability, can seldom be used as a mopping or working face.

SUMMARY OF THE INVENTION

The present invention looks to the provision of a mop head which is generally square in cross section, and has a pair of spools which permit 90° rotation on the host wringer mop. As a result of the 90° available rotation, by reciprocating the mop back and forth, it will flip flop between one face on the pushing stroke, and one face on the pulling stroke, thereby utilizing two of the four faces of the mop head. By reversing the mop head on the wringer mop assembly, the opposite two faces are similarly used. Thus the wear, dirt absorption, water absorption, and cleaning faces may be distributed over the entire periphery of the mop head.

In accordance with another aspect of the invention, the mop head is molded of a cellulose-type sponge, providing it with a chamois-like exterior surface, and optionally providing a reinforcing mesh closely adjacent the surface to significantly lengthen the life of the mop head assembly against abrasion primarily encountered in washing walls and other rough surfaces. When the reinforcing mesh is substantially a cotton base material, good absorption of water occurs through the wicking action assist to the sponge given by the cotton.

In view of the foregoing it will become apparent that one of the principal objects of the present invention is to provide a wringer mop replaceable head which is so constructed that, in combination with a particular wringer mop, it will flip flop in operation utilizing two of the four adjacent faces, and be reversed to utilize the other two adjacent faces to the end that wear, water absorption, and dirt retention may be uniformly distributed over the entire face of the mop head.

Still another object of the present invention is to provide a mop head of the character set forth in which the same can be immobilized where one fixed position of the mop head is desired.

A further object of the present invention is to provide a wringer mop replaceable head with a reinforcing element which does not impede the moisture retaining or expressing characteristics of the mop, and yet significantly improves the strength characteristics of the material in wringing usage as well as washing and scrubbing abrasive-like surfaces.

Still another object of the present invention is to provide a mop head of the character described which insures a relatively inexpensive replaceable construction.

DESCRIPTION OF ILLUSTRATIVE DRAWINGS

The foregoing objects and advantages as well as the inventions embodied herein will be better understood taken in conjunction with the accompanying illustrative drawings in which:

FIG. 1 is a plan view in disassembled form of the replaceable mop head and its associated wringer mop.

FIG. 2 is an end view partially diagrammatic illustrating the motion of the mop head as the same is moved up and down a wall surface.

FIG. 3 is a sequential view related to FIG. 2 illustrating how the flip flop of the mop, depending upon the direction in which it is moving, affects the face which is engaging the wall.

FIG. 4 is a further sequential view of the mop head as shown in FIG. 3 illustrating the same after it has been reversed 180° on the wringer assembly.

FIG. 5 is a further sequential view illustrating how the final mop head face is engaged by the wall surface, immediately subsequent to its positioning as shown in FIG. 4.

FIG. 6 is an end view of the subject mop head illustrating the same in its fixed or rigid position in which no "flip flop" occurs.

FIG. 7 is a perspective, partially broken view of the mop head illustrating the interior reinforcing fabric, the cutout portion, and the means for securing one spool to one end.

FIG. 8 is an enlarged fragmentary broken view illustrating one type of reinforcing mesh employed in the manufacture of the mop head.

FIG. 9 is another enlarged fragmentary view illustrating another type of material employed for reinforcing the interior of the mop head.

FIG. 10 is a perspective view of the anchor spool and its associated cap which are fixed at one end to the illustrative mop head.

FIG. 11 is a longitudinal transverse section of the anchor spool shown in FIG. 10 taken along section line 11-11 of FIG. 7.

FIG. 12 is a transverse sectional view of the anchor spool taken along section line 12-12 of FIG. 11.

FIG. 13 is a perspective view of the wringer spool and its associated cap.

FIG. 14 is a longitudinal section of the wringer spool taken along section line 14-14 of FIG. 7.

FIG. 15 is a transverse sectional view of the wringer spool taken along section line 15-15 of FIG. 14.

FIG. 16 is one of three sequential views showing how the ring is clamped around the anchor spool, the cross

section being taken at section line 16—16 of FIG. 11.

FIG. 17 is a sequential view in the formation or completion of the banding showing, in the same scale and from the same viewpoint as FIG. 16, the second step of forming a dent in the ring.

FIG. 18 is a final view taken from the same vantage point and in the same scale as FIG. 16 and 17 showing how subsequent squeezing of the ring causes the dents as shown in FIG. 17 to become curled pigtails as shown in FIG. 18, completing the banding of the end of the cellular sponge block.

DESCRIPTION OF PREFERRED EMBODIMENT

The mop head 20 illustrative of the present invention is best understood in its environment as removably secured to a wringer type mop holder 10 of the character shown in FIG. 1 of the accompanying drawings. There it will be seen that the wringer mop holder 10 is secured at the end of a handle 11 and includes as its principal body portion a U-shaped head mount 12. A wringer 15 having a wringer crank which is actuated by turning the same with the operator grasping the handle 27 is secured at its rotating end to the base of the wringer shaft 25. The wringer shaft 25 is mounted in a wringer shaft support 28 having a pair of diametrically opposed anchor spool engaging fins 30. At the far end or free end of the wringer shaft 25 provision is made for a rotatable wringer snap assembly 35 which has at the end of its body portion a snap head 43 and extending diametrically from the body portion in axially aligned orientation with the anchor spool fins 30 are a pair of wringer snap assembly fins 53. The anchor spool engaging fins 30 and the wringer spool engaging fins 53 are positioned in axial alignment for engagement with their corresponding anchor spool 31 and wringer spool 36 of the mop head 20.

The mop head 20 has an interior body formed from a sponge block 50. The particular type of sponge material conveniently employed in the making of the subject mop head is illustrated in U.S. Pat. No. 2,280,022. There it will be seen that a cellulosic pasty mass may be molded or extruded to form the sponges. One form of extruding such a mop head, with a cloth 40 at its exterior, is illustrated in U.S. Pat. No. 2,913,772. Referring to FIGS. 1 and 7, it will be seen that the cellular sponge 50 appears interiorly of the mop head 20, and the reinforcing mesh 40 is immediately adjacent the exterior of the mop head 20. In actual form, because the mop head 20 is molded, a skin develops on the surface of the cellular sponge material, and the skin has a chamois-like consistency. The mesh 40 serves to reinforce the surface, and particularly the corners of the generally square cross section mop head 20 against tearing, and further against abrasion.

As illustrated in FIG. 8, an open weave-type mesh 40 may be employed, or as illustrated in FIG. 9, a woven webbing may be employed. In some instances a nylon or polyester reinforcing webbing 40 will be preferable, particularly in those cases where rough surfaces are to be washed. On the other hand, where repeated wringing, but less abrasive surfaces are to be encountered such as kitchen floors, parkay floors, composition floors and the like, then a mercerized or even knitted cloth 40 will blend into the surface of the mop head 20 and further augment the chamois-like effect on the ac-

tual mopping, leaving a smooth or even polished finish in the drying effort.

One aspect of the invention looks to the flip flop arrangement whereby two adjacent faces are utilized in reciprocatingly stroking the mop. By first referring to FIG. 2, it will be seen that the mop is being pushed upwardly against the wall W as shown in the direction of the straight arrow. The effect of the friction against the surface engaged by face A is to attempt to rotate the 10 mop head in the direction of the curved arrow. This is resisted by the engagement of the fin 53 at the end of the flip flop slots 38 against the ends of the flip flop slots 38 which define the fixed head slots 39.

At the end of the stroke in the pushing direction as 15 shown in FIG. 2, the mop head is then returned toward the user in the direction of the straight arrow shown in FIG. 3. This causes the mop head 20 to rotate in the clockwise direction as illustrated by the curved arrow, and reverse the operative face from face A to face B 20 against the wall W, with the fins 53 remaining in the same relative position, but at the opposite ends of the flip flop slots 38 and abutting the opposite member which defines the fixed head slots 39.

In FIG. 4, the configuration is shown in which the 25 mop head 20 is rotated 180° from that shown in FIG. 2. Thereafter when the mop head 20 is pushed in the direction of the straight arrow or up the wall W as shown in FIG. 4, the tendency is to roll in the direction of the curved arrow at the lower portion of FIG. 4, 30 thereafter abutting the fin 53 in the flip flop slots 38 as illustrated. On the return stroke, the direction of effect of the mop head 20 is that as shown at the curved arrow, and as illustrated in FIG. 6 the face D is presented to the wall W as the mop head 20 is moved in the direction of the straight arrow shown in FIG. 6, or towards the user. Thus by turning the mop head 20 180°, instead of operating on faces A and B in the configuration as illustrated in FIGS. 2 and 3, the mop head works on faces C and D as illustrated in FIGS. 4 and 5. In this 35 fashion, all four faces of the mop head, by regularly rotating the same 180°, can be subjected to the same amount of wear, and of course, the same amount of exposure to dirt prior to any cleaning steps which may be undertaken. As illustrated in FIG. 6, the fixed head slots 39 can be employed to engage the fins 53, and 40 then the mop head 20 becomes positively fixed onto the mop for such operations as wiping the top of doors, going under flat surfaces such as under couches, beds, and the like.

The specifics of the mop head 20 are shown in the 50 cutaway view of FIG. 7. There it will be seen that the sponge body is encased by the reinforcing mesh 40, and banded at its two ends to the respective anchor spool 31 and wringer spool 36. More particularly, rings 61, 55 62 are employed at each end and secure the end of the reinforced sponge to the respective spools. The interior portion of the sponge 50 is provided with a wringer shaft bore 52. Prior to securing the rings 61, 62 in place to secure the ends of the sponge 50 to the anchor spool 31 and wringer spool 36, the transverse cross section of 60 the mop head sponge 50 is substantially uniform. In a successful commercial embodiment, the distances across the faces of the sponge block 50 are approximately 3½ inches, making the same a 3½ inch square. 65 The length of the mop head 20 may vary between 8 and 10 inches. Variations in these dimensions are contemplated as within the scope of the invention, the same

being set forth for purposes of illustrating a desirable commercial embodiment, and desirable proportions.

As observed in FIGS. 1 and 7, the mop head 20 is finished at its respective ends by the provision of a pair of end caps 41, 42. The anchor spool end cap 41 is provided with an opening 46 at the central portion. The wringer spool and cap 42 is imperforate at its end. Each of the end caps is provided with skirts 60 having annular internal snap rings 48, 49. The anchor cap snap ring 48, and the wringer cap snap ring 49, are of substantially the same configuration, and are proportioned to press-fittingly pass over the end of the wringer spool 36 and anchor spool 31 and lock in place with the skirts 60 approaching the sponge block 50 to mask the ring and its banded portion of the end of the sponge block 50. Alternative means for press-fittingly engaging the end caps 41, 42 are contemplated, such as male and female member snap fits respectively on the end caps 41, 42 and the anchor spool and wringer spool 31, 36. The purpose of the end caps is to provide a more finished look to the product, and also a smooth surface which is less likely, at the wringer spool end cap 42, to scratch mop boards, table legs, and the like.

Referring now to FIG. 10, specifics of the anchor spool 31 will be seen. It should be noted that the anchor spool 31 contains a pair of flip flop slots 32, and a pair of fixed head slots 34. The flip flop slots comprise approximately 90° of the arcuate portion, and the fixed head slots 34 are oriented at an approximate perpendicular axis to the center axis of the flip flop slots 32. To be noted also are the stabilizing fins 55 around the exterior of the anchor spool 31 for purposes of securely locking the sponge block 50 when banded by means of the ring 61 to the ends of the sponge block 50.

As illustrated in FIGS. 10, 11, and 12, an undercut 58 is provided to receive the sponge block 50 portion which is securely tightened and banded by means of the tie ring 61. The wringer spool 36 is illustrated in FIGS. 13, 14, and 15 where it will be seen, particularly in FIG. 14, that a snap head collar 37 is provided in the wringer spool 36 to fit in the undercut 45 at the end of the wringer shaft (see FIG. 1) adjacent the snap head fastener 43. Interiorly, a plurality of flip flop slots 38 and fixed head slots 39 are provided in the wringer spool 36, just the same as in the anchor spool 31. Also an undercut 59 is provided to receive the wringer spool ring 62, in the same fashion as with the anchor spool 31.

The banding of the ends of the sponge block 50 is shown diagrammatically and sequentially in FIGS. 16 through 18. The end of the sponge block 50 is first squeezed and then (for purposes of illustration the anchor spool portion is shown which is substantially identical to the wringer spool portion) the anchor spool ring 61 is placed in position over the already shrunken end of the sponge block 50. It will be noted that the ring 61 is formed of a thin band of stainless steel with a welded overlap 68. The first step in banding is to squeeze the ring 61, and form a pair of diametrically opposed dents 63 (see FIG. 17) at a position adjacent the single horizontal stabilizing fin 55. As will be noted particularly in FIG. 17, the dents 63 have their pointed ends resting on auxiliary teeth 69. When the ring 61 is subsequently subjected to further squeezing (see FIG. 18), the formation of the pigtails 67 in offsetting directions as shown in FIG. 18 results. The thus formed pigtails 67 serve additionally to the auxiliary teeth 69 and fins 55, 56 to lock the end of the sponge block 50 as

banded by the ring 61 against the anchor spool 31, or the wringer spool 36. It will be further noted that the ring 61 defines a circular locus slightly less than the circular locus of the stabilizing fins 55. As shown in the other section in FIGS. 11 and 14, the band or ring 61, 62 thus serves to tightly tie the end of the sponge block 50 to its associated spool, and the same translates the motion or anchor action of its respective spool 31, 36 to the sponge 50, and yet any unsightly appearance of the slant end of the sponge block 50 is masked by means of the respective end caps 41, 42 and their depending skirts 60.

As to the material employed, as indicated above, the cellulose sponge is a regenerated cellulose, preferably having a high content of flax for reinforcing purposes. The reinforcing mesh 40 in a commercial embodiment is a Raschel knit of 90° to 100° cotton made by Southern Mills, Inc., of Atlanta, Ga. The warp yarns are 10/2²-2 warps and 32/2²-1 warp. All are made from good grade, clean, carded cotton or blended of 22 percent with nylon or another polyester to prevent shrinkage, and further increase strength. They are knitted on 18-gage or 36-gage machines, with two needles for each hole in the netting, 16-18 stitches per inch after dyeing and tentering. The same is thereafter sewn into a sleeve which, after sewing, contains 38 holes around the periphery of the sleeve or between 3 and 4 holes per inch. The sleeve is cut to approximately 46 inches in length with one end closed. Thereafter the sleeve is positioned in a mold and the reinforced cellular sponge block formed generally as described in the Buchkremer U.S. Pat. No. 2,913,772, owned by applicant's assignee. The blocks are then cut off to the particular lengths of sponge block 50 which is to be employed in the molded mop head.

In summary, it will be seen that a mop head 20 has been shown which can be used on a wringer mop assembly 10 which is susceptible of reciprocating use on all four of the faces, the faces of the mop head 20 (A, B, C, and D) being approximately the same size, weight, and proportion. By reversing the mop head 20 180°, the two faces can be used in reciprocating mopping, which are not used prior to reversal. In addition, a fixed position is provided for those applications where the mop head 20 is to be rigidly secured to the mop assembly 10. Reinforcing material is provided in the sponge block 50, such as a mesh 40, or other open weave material which assists in reducing the tendency of the sponge 50 to tear, or wear during repeated wringings, and washing against roughened surfaces. By molding the sponge 50, rather than sawing the same from a large bun, the exterior surface of the mop head 20 is chamois-like and preserves a good finish, and yet without any loose cloth on the exterior of the mop head which can become shredded by working on rough surfaces such as painted walls.

Although particular embodiments of the invention have been shown and described in full here, there is no intention to thereby limit the invention to the details of such embodiments. On the contrary, the intention is to cover all modifications, alternatives, embodiments, usages and equivalents of a mop head as fall within the spirit and scope of the invention, specification and the appended claims.

What is claimed is:

1. For use with a wringer type mop holder, a cellular sponge mop head comprising, in combination,

a molded sponge body,
said body being substantially square in cross section
and having four faces of substantially the same con-
figuration,
a wringer spool secured at one end of said sponge
member,
an anchor spool secured at the other end of said head
each of said anchor spools and wringer spools having
opposed flip flop slots, and,
means for snap fittingly securing said mop head as-
sembly to a wringer type mop holder whereby upon
reciprocating the mop, at each stroke reversal, al-
ternate adjacent mop head faces engage the
mopped surface.

2. In the mop head assembly of claim 1 above,
a reinforcing material molded into the mop head
sponge body immediately beneath or coextensive
with the surface portion thereof,
whereby the mop head assembly is reinforced against
wear on roughened surfaces and at the edges adjacent
the four faces to resist tearing in repeated wringing.

3. In the mop head assembly of claim 1,
a pair of opposed head slots on each of said anchor
spool and wringer spool for fixing the assembly on
the holder.

4. In the mop head assembly of claim 2,
said material comprising an open weaved mesh of
synthetic fibrous material.

5. In the mop head assembly of claim 1,
a pair of end caps,

means on said end caps proportioned to snap fittingly
engage the respective anchor spool and wringer
spool ends.

6. In the mop head assembly of claim 2,
said fabric comprising a knitted fabric and molded
substantially coplanar with the exterior skin of said
sponge portion.

7. In the mop head assembly of claim 1,
a plurality of stabilizing fins on each of said wringer
spool and anchor spool and extending therefrom.

8. In the mop head assembly of claim 7,
tie rings employed to clamp said sponge body at its
ends to the respective anchor spool and wringer
spool.

9. In the mop head assembly of claim 8,
undercut means on each of said wringer spool and
anchor spool to receive the gathered end portion of
said sponge body.

10. In the mop head assembly of claim 9,
a pair of end caps proportioned to snap fittingly en-
gage the respective anchor spool and wringer spool
to mask the tie rings and finish the ends of the mop
head to mask the tied end portions of the sponge
body extending beyond the tie rings.

11. In the mop head assembly of claim 1,
said body having a length at least twice its width.

12. In the mop head assembly of claim 10,
said body having a length at least twice its width.

* * * * *
